UNITED STATES PATENT OFFICE.

RAYMOND H. MITCHELL, OF ROYERSFORD, PENNSYLVANIA; ESTHER D. IRWIN
MITCHELL, ADMINISTRATRIX OF SAID RAYMOND H. MITCHELL, DECEASED,
ASSIGNOR TO SANITARY COMPANY OF AMERICA.

VALVE.

1,177,533.

Specification of Letters Patent. Patented Mar. 28, 1916.

Application filed August 14, 1909. Serial No. 512,809.

To all whom it may concern:

Be it known that I, RAYMOND H. MITCHELL, of Royersford, in the State of Pennsylvania, have invented a certain new and useful Improvement in Valves, whereof the following is a specification, reference being had to the accompanying drawings.

My invention relates to a valve designed for use in connection with a hopper closet 10 provided with a flush tank and connections for automatically flushing the hopper with water from said tank.

It is the object of my invention to prevent the freezing of water in such a closet by 15 providing means for discharging into the drain pipe below the hopper all of the water supplied to the flush tank and hopper connections during the flushing operation, so that under normal conditions, except during 20 the momentary operation of flushing, all of the water pipes above the frost line are empty.

The form of hopper closet embodying my invention hereinafter described includes the 25 combination with a hopper having a waste pipe, a flush tank, and means to supply water under pressure to said tank; of a valve arranged to be operated by the pressure of water toward said tank to obstruct 30 the flow of water from said tank to said hopper, and operated by the pressure of water away from said tank to permit the flow of water to said hopper. The invention herein claimed relates solely to said 35 valve.

In the drawings; Figure I is a side view of a convenient embodiment of my invention, in connection with a section of a floor. Fig. II is a fragmentary sectional view of 40 the tank and a portion of the hopper indicated in Fig. I, but on a larger scale. Fig. III is a partial sectional view of the water supply controlling valve indicated in Fig. I.

The hopper 1 supported by the floor 2, in 45 connection with the waste pipe 3, and trap 4, has the water flush tank 6, provided with the conduit including the vertical pipe 7, valve casing 8, and horizontal pipe 9, through which the water from said tank 50 may be emptied into the hopper 1.

Water is supplied to said tank through the pipe 10 under control of the automatic valve including the reciprocating cup mem-

ber 11, fitted to slide in said casing 8, and having at its top the port 13, provided with 55 the check valve 15, arranged to rise and fall upon the studs 16, which retain it in operative relation with said valve member 11. The arrangement is such that when water is supplied under pressure through 60 said pipe 10, beneath said valve member 11, the latter is raised to cover the port 18 in said casing 8, leading to the horizontal pipe 9, so as to obstruct and prevent the flow of 65 water from said tank to said hopper. The supply of water through said pipe 10 to the tank 6 and hopper 1 is controlled by the 70 automatic valve comprising the casing 20, to which the water is directed by the pipe 21 from the source of supply. Said casing 20 is also in communication with the waste pipe 3 through the drain pipe 22. Said valve casing 20 is supported by the bracket 24 adjustably 75 connected with the waste pipe 3, by the bolt 25, and has the arm 26 carrying the cam ring 27 beneath the cam disk 28. Said disk 28 is adjustably connected with said arm 26 by the bolt 30 and the arrangement 80 is such that said ring 27 and disk 28 may be clamped in adjusted relative rotary position so as to present the upper surface of said disk 28 in a horizontal plane regardless of the inclination of said drain pipe 3 and bracket 24. Said casing 20 contains 85 the plunger valve 32 having the stem 34 and the spring 35 which normally maintains said stem and valve to be lowered against the pressure of said spring 35 when the seat 37 is pressed downward upon said stem. Said seat is hinged at 38 and provided with 90 the weight 39 to raise it to the position shown, whenever released. It is to be understood that the arrangement of said controlling valve 32 is such that when it is released and assumes the position shown in Fig. 1, the 95 passageway 40 connecting the pipe 21 and the pipe 10, is closed and the passageway 41 connecting the pipe 10 and the pipe 22 is opened, so that when said seat is raised, as shown, the water from said tank is emptied 100 into said hopper and the water in the valve connections 12 beneath the valve member 11, in the pipe 10, and the valve casing 20, is discharged through said drain pipe 22, into the waste pipe 3, below the hopper. However, when said seat is depressed upon said 105

valve stem and the valve thus shifted to its lower position said passageway 41 is closed and the escape of water through said drain pipe 22 is prevented while the flow of water 5 from said supply pipe 21 to the pipe 10 and tank 6 is permitted. The aperture 42 in said valve member 11 permits the passage of air as the water rises and falls beneath said member. I also find it convenient to 10 provide the tank 6 with the overflow pipe 43 establishing communication between said tank and the hopper 1 through the pipe 9 independently of said valve 11, so that all 15 water rising in said tank above the top of said pipe 43, will be discharged directly into the hopper.

I do not desire to limit myself to the precise details of construction and arrangement herein set forth, as it is obvious that 20 various modifications may be made therein without departing from the essential fea-

tures of my invention as defined in the appended claim.

I claim:

The combination with a casing; of a hollow cylindrical cup valve mounted to reciprocate in said casing, and having a port; a check valve carried by said cup valve including a loose plate adapted to cover said port; and means independent of said check valve limiting its opening movement, including a pair of studs extending through said plate and having heads serving as stops for said plates.

In testimony whereof, I have hereunto signed my name, at Linfield, Pennsylvania, this 29th day of July, 1909.

RAYMOND H. MITCHELL.
